UNITED STATES PATENT OFFICE.

GEORGE L. HARVEY, OF CHICAGO, ILLINOIS.

CAR-TRUCK.

SPECIFICATION forming part of Letters Patent No. 613,415, dated November 1, 1898.

Application filed August 27, 1898. Serial No. 689,698. (No model.)

To all whom it may concern:

Be it known that I, GEORGE L. HARVEY, of Chicago, in the county of Cook and State of Illinois, have invented certain new and useful Improvements in Car-Trucks, of which the following is a specification.

Car-trucks require, by reason of the immense loads they carry and the shocks and jars of service, to be substantially constructed and of as few parts as is consistent with strength and the provisions for mounting the axle-boxes and springs therein.

Car-trucks have heretofore been made of a variety of materials, including bars of metal of various forms, steel plates pressed to shape, and the like.

Car-trucks of the rigid type, to which my invention relates, have pedestals forming guides for the axle-box and provisions for mounting the springs over the box. These provisions necessitate the extension of the side members of the truck to the outer pedestal or guide, and heretofore it has been the common practice where the truck is composed of pressed steel to arch the ends of the side members, so as to span the axle-box. Where the trucks have been made with side members composed of metal beams, it has been common to rivet or otherwise secure to the ends of the side members an arched hanger whose vertical portion formed the outer guide for the box, while the arched portion took the thrust of the spring. To press a plate of steel into form to provide this arch and guide at its ends requires exceedingly heavy and expensive machinery. The other form of construction described has not sufficient strength, because it does not embody adequate support for the outer guides.

It is the object of my invention to provide a car-truck having the necessary strength and which may be manufactured of easily-obtainable materials and without the employment of heavy and expensive machinery. To attain this object, I use for the side members of the truck steel plates, beams, or bars, many suitable forms of which can be obtained in the market, while special forms adapted to my purpose may be readily produced and adapted. These side members are laterally offset at their ends, and their extremities

either form or support the outer guides, the offsetting being sufficient to extend around the spring upon one or both sides thereof. I employ, preferably, as the basic element of the side-frame member of the car-truck a flanged beam and have found a channel-beam best suited to my purposes. These beams are procured or cut to a length so that the end portions thereof may be laterally offset to pass the spring and to afford an outer bearing guide or support.

In the preferred construction I take two channel-beams and cut away their lower corners and bend the unsevered portions laterally and preferably on curved lines tangential to the body of the beam. The severing is also preferably done upon curved lines, thus leaving a vertical web portion of greater depth than the intermediate curved portion of the web, this terminal web portion serving as a support for the outer guide. Two of these channel-bars thus formed are placed back to back and riveted together, and in order to form a bearing for the spring and guides for the box I employ spring-yokes composed of T-bars, the latter being bent with the head upon the inside of the yoke, the webs presenting outwardly, and riveted between the webs of the channel-bars.

In the accompanying drawings, Figure 1 is a broken plan, partly in section; Fig. 2, a partial side elevation; and Fig. 3, a section on the line 3 3 of Fig. 2, looking in the direction of the arrow, said views showing the preferred construction. Figs. 4 to 17, inclusive, represent modifications of the invention, Figs. 4, 5, and 6 showing in plan, sectional elevation, and side elevation, respectively, a construction wherein a single channel-bar is employed in the side member of the truck. Figs. 7, 8, and 9 are similar views showing plate side members. Fig. 10 is a sectional elevation showing a side member composed of a beam having a single flange. Figs. 11 and 12 show a single plate without flanges. Figs. 13 and 14 show a side member formed of a composite beam composed of a plate and two angles. Figs. 15 and 16 show in sectional and side elevation a side member composed of a plate with two small channels riveted thereto, and Fig. 17 is a broken plan view showing a

single channel-bar side member with a strap or plate riveted thereto and intended to pass on the inside of the spring.

In the drawings, referring first to Figs. 1, 5 2, and 3, the side members are composed of the channel-bars 20 21, which are cut to a length slightly in excess of the extreme length of the side bar when completed. The lower corners of these channel-beams are cut away 10 to receive the axle-boxes 22, and the remaining portion of the ends of these channel-bars are subjected to the action of a suitable press or bulldozing-machine to produce therein the lateral oval pocket or enlargement 23, and 15 the margins of the webs of the channel-bars are swaged out to provide the transverse stiffening-flanges 24. By reference to Fig. 2 it will be seen that the webs at the extremities or ends of the channel-beams extend below the flanges 24, and these depending portions (marked 25) give additional riveting-surface and bearings for the spring-yokes 26. These latter are preferably constructed of T-bars, the webs of the bars being secured between 20 the channels 20 21, which are placed back to back and separated by said webs and by suitable filling-pieces between their ends. The T-bar also has its head or flange bent from the flange 24 to the top of the channel-beam to conform to the curved surfaces of 25 the webs of said beams. The head of the T-bar, forming the inner surfaces of the yoke, affords a suitable bearing upon the spring-cap 27, by which the spring 28 is confined on top 30 of the box 22, while the lower extremities of the yoke extend below the channel-bars and afford bolt-lugs 29 for the bolt 30, which passes beneath the box and prevents the separation of the latter from the truck. The extremities 35 of the T-bar, forming the yoke, constitute the pedestal of the truck and are embraced by flanges or lips on the box in the usual manner. The flanges of the channel-bar 21 are cut away parallel to the face of the wheels, 40 as shown at 31 in Fig. 1.

As my invention has to do mainly with the side members of the truck, it is obvious that such side members may be connected in any preferred manner. I preferably employ channel-bars arranged at right angles to the side members and such as shown at 32 in Fig. 1. Said channel-bars may fit in between the flanges of the channel 21 and be secured thereto by the knee-pieces 33, and for further 45 security the gusset-plate 34 may be riveted to the flanges of the side members and overlap the connecting members 32.

The construction just described is preferred for the reason that while the materials employed are such as may be obtained readily and easily worked or adapted a very strong and serviceable truck is afforded, and such a truck will be found adequate to meet the demands for cars designed to carry heavy loads 60 and any service requiring a strong and rigid construction. The principle of my invention, however, may be embodied in cars of lighter

construction where, from consideration of economy, it may be desired to make a lighter truck. To meet these requirements, I have 70 illustrated in Figs. 4 to 17, inclusive, various modifications, and it will be understood that others may be made within the scope of my invention. In the construction shown in Figs. 4, 5, and 6 I have simply omitted one 75 of the channel-bars. In the construction shown in Figs. 7, 8, and 9 plates 35 36 are used as the side members of the truck, and these plates, while of simpler and cheaper form than channel-beams, can be more readily 80 bent, but do not, of course, afford the same strength. In Fig. 10 another suggested modification is in the employment of an angle-beam 37, having a long web and narrow flange, and two of these might be used placed back 85 to back. In Figs. 11 and 12 I have shown a single plate member bent to embrace the spring and affording an outer support for the yoke. In Figs. 13 and 14 I have illustrated a composite beam made up of the plate 38 and 90 the angles 39. In Figs. 15 and 16 I show a plate 40, having a channel 41 riveted thereto and a second channel 42 spanning the spring-pocket. In Fig. 17 I have shown a channel as the principal element of the side member, 95 with a simple inner strap 43, curved to embrace the spring-pocket.

It will be seen that all of the forms above described are such as are readily obtainable and easily worked, the several plates, beams, 100 and bars being of ordinary shapes; further, that the shaping of these several beams or bars to receive the spring may be readily accomplished without the use of expensive or heavy machinery. The cutting away of the 105 corners of the beams reduces the width, so that the remaining portion is readily bent to form the spring-pocket. It is also obvious that the several forms of construction above described all embody the same general principle of carrying the side member of the truck around the spring, so as to afford an outer support for the yoke or outer member of the pedestal, such outer support being integral with the body of the truck, and thus secures 110 a rigidity which would be impossible to secure were the yoke or pedestal to be hung to the ends of the side members of the truck. While other variations than those described or suggested may be made, I regard the employment 115 of the yoke in combination with the extended end of the side member as being highly important. I also prefer a yoke of the form shown, as it adds strength to the truck instead of detracting therefrom and is for that 120 purpose preferably made in a single piece, its web or body serving as a suitable filling between the side members where two are employed and as a brace or tie spanning the curved or offset portion of the side member. I also prefer in all cases to employ flanged 125 beams, as well as the strengthening-flange formed by turning out the web of the side member adjacent to the spring-pocket.

The two features of my invention which are considered especially important and which are common to the several constructions shown and described are the provision of a side member for a car-truck outwardly or laterally curved or offset at its extremity to provide a spring-pocket and the employment therewith of an upwardly-arching yoke connected to the beam at the sides of the spring-pocket and affording also a pedestal or guides for the boxes.

I claim—

1. A car-truck having its side members composed of flanged beams, arranged back to back, and with their flanges projecting outwardly, said beams being outwardly or laterally curved, or offset to provide a spring-pocket, substantially as described.

2. A car-truck having its side members composed of flanged beams, arranged back to back, and with their flanges projecting outwardly, the lower outer corners of said beams being cut away to afford space for the axle-box and the unsevered portions being offset laterally to provide a spring-pocket, and their extremities joined to afford an outer bearing or support for the pedestals, substantially as described.

3. A car-truck comprising in its construction, a side member, composed of channel-beams placed back to back, and having their lower corners cut away to receive the axle-boxes, the central portions of said cut margins being bent out to provide strengthening-flanges, and the extremities depending below said flanges for attachment to the pedestal members, substantially as described.

4. A car-truck having a side member composed of channel-beams, arranged back to back and with their lower corners cut away to receive the axle-box, and the unsevered portions laterally offset to receive the spring,

the lower margins of such offset portions being flanged, and a yoke or pedestal member secured with the channel-beams and adapted to embrace a spring and axle-box, substantially as described.

5. A car-truck having in combination, a side member composed of channel-beams arranged back to back, with their lower corners cut away to receive the axle-box, and the unsevered portions laterally separated to provide a spring-pocket, and a yoke or pedestal member, having a flange thereof embraced between the channel-bars and secured thereto on opposite sides of the spring-pocket and the extremities of said yoke or pedestal affording guides to the box, substantially as described.

6. A car-truck having a side member having its ends outwardly or laterally curved or offset to provide a spring-pocket, and a yoke having the legs thereof secured to the beam or bar on opposite sides of said curved portion, substantially as described.

7. A car-truck having a side member composed of a beam, the extremities thereof being laterally curved or outwardly offset to pass around the sides of the springs, and a yoke upwardly arched or curved and adapted to pass over the springs and having the legs thereof connected to the side member adjacent to the offset portion thereof, substantially as described.

8. A car-truck having a side member composed of two beams or bars arranged parallel to each other and having their terminal or end portions outwardly curved or offset to embrace the spring, substantially as described.

GEORGE L. HARVEY.
